UNITED STATES PATENT OFFICE.

SAMUEL E. BARLOW, OF DENVER, COLORADO.

MULTIPLE-HOIST PUSH-CAR.

1,351,225.

Specification of Letters Patent. Patented Aug. 31, 1920.

Application filed June 28, 1919. Serial No. 307,396.

To all whom it may concern:

Be it known that I, SAMUEL E. BARLOW, a citizen of the United States, residing at the city and county of Denver and State of Colorado, have invented certain new and useful Improvements in Multiple-Hoist Push-Cars; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to hoisting devices, and more particularly to a push car or the like, upon which a plurality of hoists is mounted for the purpose of handling rails. The object of the invention is to make it feasible to place rails which have been removed in track-repair, in the middle of the track and to then move them by the present invention to some general assembly point. It is often desirable to place removed rails in the middle of the track, as on bridges, trestles, in narrow cuts and tunnels, and at stations. It is also desirable to place the rails in the middle of the track at other points in order to leave the sides of the track free for trainmen and other railroad employees who are obliged to walk along sides of trains and strings of cars for inspection purposes or the like, as well as to render it safer for passengers alighting from trains.

Briefly, the invention comprises a push car equipped with wheels and a framework upon which there is mounted a multiple hoist, each part of which is provided with a clutch, a ratchet and a dog, whereby one rail or several rails may be handled independently and suspended in position. The device also comprises means on the under side of the framework for maintaining the rails in position when suspended.

In the drawings:

Figure 1 is a side elevation of the invention.

Fig. 2 is chiefly an end elevation, taken on the line 2-2 of Fig. 1.

Figs. 3 and 4 are detail views of the clutch and ratchet mechanism, showing the clutch in and out of engaging position, respectively.

Fig. 5 is a modification of means for positioning the rails when suspended, and also is designed to indicate a method of unloading the rails from the hoist.

The framework of the push car comprises longitudinally extending beams 10, and cross bars 12, there being journaled at 14 on the under side of the beams 10, axles 16, upon which are mounted wheels 18. Upon opposite ends of the car spaced platforms 20 are provided, and upon these are mounted standards 22, carrying a shaft 24, journaled thereon at 26, said shaft carrying a large gear wheel 28, with which there meshes a small gear 30, adapted to be rotated by means of a crank 32. Gear wheel 30 is mounted upon a shaft 34, also journaled on the standards 22 (by means not shown), this shaft being equipped with a brake drum 36, over which passes a brake band 38, connected with a brake pedal 40, hinged to one of the platforms 20 at 42. Splined upon the gear shaft 24 is a plurality of movable clutch parts 50, adapted to engage clutch parts 52, connected with ratchets 54, each of which carries a pulley member 56, receiving the hoist chains 58, which carry at their lower ends tongs 60, for lifting rails, or other devices, such as hooks 62, for elevating any other objects that may have to be handled. A cross rod 64 is mounted on the standard 22 adjacent the shaft 24, and upon this rod 64 there are mounted dogs 66, adapted to engage the ratchets 54. On the opposite side of the shaft 24, another rod 70 is mounted, this rod carrying levers 72, for operating the clutch members 50. Secured to the ends of the car on the under side thereof are cross beams 80, supported from the beams 10 by means of brackets 82, bolted to the beams 10 at 84. These cross beams 80 carry a plurality of spacing members 86, adapted to retain the rails R, indicated in dotted lines in Fig. 2, in position when elevated, in order to prevent them from swinging from side to side, as they are carried along. A compressible material 88, of any suitable character, is secured to the under side of the cross beams 80 to cushion the rails R when drawn up against the beams.

In the modification shown in Fig. 5, a cross beam 92 is shown suspended from the beams 10 and held in spaced position by

brackets 90. In this form a plurality of wooden blocks 94, of the design shown, are nailed or bolted to the under side of the beams 92, the bottoms of the spaces between these blocks being filled with compressible material 96, against which the rails R may be drawn.

In Fig. 5 a bar 100 is shown in position, this bar being used in unloading the rails 10 and discharging them beyond the track in a manner presently to be described.

In operation of the device, it is assumed that rails which have been removed from the track in repairing are located in the 15 middle of the track ready for removal. If only one rail is to be raised from this point, one of the clutches 50 will be thrown in, the corresponding tongs 60 will be engaged with the ball of the rail, and by means of 20 the crank 32 and the gears 30 and 28, the chain 58 is wound up on the pulley 56 and the rail R is pulled up against the compressible material, as indicated in Fig. 5, this material having sufficient compressibility to 25 permit it to compensate for the slight retraction of the ratchet 54 when it falls back into engagement with its dog 66, the rail still being in engagement with the compressible material. This, together with the 30 spacing members 86, or blocks 94, as the case may be, securely retains the rail against movement. The car is then moved along into position to remove another rail. The clutch 50 for the rail already suspended is 35 thrown out, and another rail elevated with another clutch by the same process. In this manner, one or more rails are elevated up to the capacity of the car. The car is then moved along to the point where the rails are 40 being assembled in bulk. Greased bars 100 are then placed across the track beneath the suspended rails, and the rails are then lowered on to the bars and released. The car, which is comparatively light, may then be 45 lifted across the bars 100, or one side of the car may be tipped up and by elevating one end of each of the bars 100, the rails R are skidded off beyond the side of the track on to the pile of rails being assembled. These 50 assembled rails are subsequently to be removed by heavy, rail-loading derricks and large, power-operated tongs.

An advantage of this invention is that it permits a quick discharge of the load in the 55 event of the sudden and unexpected approach of a train. This can be quickly done by tensing the cables 58, releasing the dogs 66, and then lowering the load through the means of the brake mechanism 36, 38 and 60 40. The car then may be quickly removed from the track or, in case that there is not sufficient time to remove the car, the collision will not be serious in view of the fact that the car carries no load.

65 From the foregoing, it will be seen that

much of the labor of eight or ten men heretofore used to load rails on a push car, and unload the same, may be dispensed with. It will also be seen that this device makes it highly practicable to move old rails into the 70 center of the track in the operation of replacing rails, which greatly facilitates the work of alinement, gaging, spiking and redressing, in connection with road repair. At the same time, the sides of the track are 75 kept free and the rails may be easily moved from the middle of the tracks.

I claim:

1. In a push car hoist, a frame, wheels thereon, and hoisting means mounted on the frame and adapted to operate between the wheels and within the frame, said hoisting means comprising a plurality of independently controlled elevating devices spaced side by side transversely of the car frame, 80 and spaced means on the under side of the car adapted to maintain rails held by said spaced devices in spaced relation when elevated.

2. In a push car hoist, a frame, wheels 90 thereon, hoisting means mounted on the frame and adapted to operate between the wheels and within the frame, said hoisting means comprising rail-engaging mechanism, and means secured on the under side of the 95 car to be engaged by the rails for prevention of lateral movement of said rails when elevated.

3. In a push car hoist, a frame, wheels thereon, hoisting means mounted on the 100 frame and adapted to operate between the wheels and within the frame, said hoisting means comprising a plurality of cables, each cable having a rail-engaging device to engage an individual rail, and spaced means 105 located beneath the car to maintain the position of the individual rails when elevated.

4. In a push car hoist, a frame, wheels thereon, hoisting means mounted on the 110 frame and adapted to operate between the wheels and within the frame, said hoisting means having rail-engaging devices, and means located beneath the car to maintain the position of the rails when elevated, said positioning means comprising spaced guides 115 and cushions, the latter being adapted to have the rails drawn into engagement therewith.

5. A method of handling rails removed during track-repair, comprising placing 120 said rails in the middle of the track and approximately parallel therewith, lifting said rails mechanically and in a path wholly between the rails of the track, maintaining said rails elevated and in said parallel position, transporting the rails in said position to a point of discharge, and discharging them beyond the track.

6. A method of handling rails removed during track-repair, comprising placing 130

said rails in the middle of the track and approximately parallel therewith, lifting said rails mechanically and in a path wholly between the rails of the track, maintaining
5 said rails suspended and in said parallel position, transporting the rails in said position to a point of discharge, placing bars across

the track and beneath the rails being handled, lowering the rails on to said bars, and skidding the rails from said bars to a point 10 beyond the track.

In testimony whereof I affix my signature.

SAMUEL E. BARLOW.
